INVENTOR

Martin F. Burns
BY E. M. Marshall
ATTORNEY

UNITED STATES PATENT OFFICE.

MARTIN F. BURNS, OF ASTORIA, NEW YORK.

DENTAL FLASK.

Application filed April 3, 1922. Serial No. 549,267.

To all whom it may concern:

Be it known that I, MARTIN F. BURNS, a citizen of the United States, and a resident of Astoria, county of Queens, and State of New York, have invented certain new and useful Improvements in Dental Flasks, of which the following is a specification.

This invention relates to dental apparatus and more particularly to dental flasks of the type used by dentists in casting plates, bridges, inlays and other restorations.

In casting a plate, bridge or other restoration a dentist first makes a pattern in wax of the article to be cast. The pattern is then invested in an initially plastic and quick hardening composition. When the investment is dry or has set the wax is melted out or otherwise dissipated, and the cavity is filled with molten metal. The casting is then allowed to cool and is preferably cooled slowly to prevent warping or distortion. When warping or distortion takes place it is necessary to swage the casting to its proper shape.

It is very desirable that the rate of heating or cooling the investment and the parts contained thereby be regulated, as different classes of work require different treatment.

This invention has for its object, therefore, to provide means in apparatus of the class described for regulating the heating or cooling of the investment and parts contained thereby.

Another object of the invention is to provide a construction by means of which the quantity of investment used will be conserved.

Another object of the invention is to provide an investment holder so constructed that the investment will be confined therein and will not engage the walls of the receptacle.

Further objects of the invention will appear from the following description taken in connection with the drawings which form a part of this application and in which—

Fig. 1 is a view showing half in section and half in elevation dental apparatus constructed in accordance with the invention.

Fig. 2 is a view taken at right angles to Fig. 1 and showing the construction half in section and half in elevation.

Fig. 3 is a view similar to Fig. 1 but showing another form of the investment holder and

55

Fig. 4 is a broken section taken substantially on line 4—4 of Fig. 3.

The invention may be briefly described as including a receptacle and an investment holder so relatively constructed and arranged that the parts may be adjusted to regulate the admission of air or heat to the spaces at the sides of the investment holder. More particularly described, the investment holder comprises spaced plates connected throughout their length to confine the investment to the space therebetween. These plates are so arranged relatively to the receptacle that spaces are formed between the plates and the wall of the receptacle. In another form of the invention, namely, that shown in Figs. 3 and 4, the space between the plates is contracted toward the lower ends thereof thereby still further conserving the investment material.

60

70

75

Referring to the drawings and particularly to the form of the invention shown in Figs. 1 and 2, the receptacle 10 has a cylindrical wall, an open upper end 11 and a bottom 12 having an opening 13 therethrough. The opening 13 is oblong in shape as clearly illustrated in Fig. 2. The wall of the receptacle 10 may have openings 10' therein to admit heat to the spaces at the sides of the investment holder, in case the heat is applied at the sides of the receptacle.

80

The investment holder comprises a pair of substantially vertical, parallel, imperforate plates 14 having their side edges closed in by connecting portions 15 extending substantially throughout the length of the walls. The portions 15 confine the investment to the space between the walls and prevent the engagement of the investment with the cylindrical wall of the receptacle.

85

As clearly illustrated in Fig. 2 the distance between the walls 14 is less than the maximum dimension of the oblong opening 13 in the bottom 12 of the receptacle and therefore the relative positions of the investment holder and the receptacle and bottom 12 thereof will determine the size of the openings to the spaces 16 formed between the sides of the investment holder and the

95

100

wall of the receptacle. By relatively rotating these parts, namely, the investment holder and the receptacle, the openings can be enlarged or contracted and thereby the admission of air or heat or if desired of a flame to the spaces can be controlled in a manner to obtain the desired heating or cooling effect.

10 Flanges 17 are formed on the upper ends of the plates or walls 14 of the investment holder and extend outwardly therefrom, the outer edges of these flanges conforming in outline to the cylindrical inner surface of the walls of the receptacle.

15 A cover plate 18 is provided for the upper end 11 of the receptacle and this plate has formed therein a central opening 19 and an outwardly extending cylindrical flange 20 forming a wall for the opening. Counter-sunk apertures 21 are formed in the cover 20 and are adapted to receive investment that is forced out therethrough thereby securing the cover of the receptacle.

25 The investment holder may if desired in this case be filled before being placed within the receptacle 10 since the space within the investment holder is enclosed by the walls 14 and 15.

30 In order to obtain a slower cooling effect I have provided a cap 22 having a packing or lining 23 for the lower end of the receptacle and a cap 24 having a packing or lining 25 for the opening 19 of the cover plate 18, this cap being adapted to fit over the cylindrical flange 20.

35 The construction shown in Figs. 3 and 4 is similar to that shown in Figs. 1 and 2 but differs therefrom in that the investment holder is contracted in section as shown at 40 30 adjacent its lower end. This contraction will conserve the investment and in no way detract from the proper functioning of the investment holder. As shown in Fig. 3 the investment holder is provided at its lower end with laterally and outwardly extending flanges 31 formed at the ends of the holder and in alinement with the connecting portions 15 thereof.

45 In operation the wax pattern is placed in the investment holder and the investment is then filled in to entirely enclose the pattern. The wax is then dissipated by heat and the cavity left by the wax is filled in with molten metal. The investment holder and the receptacle can be so relatively adjusted as to give the desired heating or cooling effects by rotating the holder and receptacle with respect to each other. This relative rotation of the parts may be more readily accomplished by the construction above described since the end walls 15 confine the investment and prevent it from engaging the wall of the receptacle. The rate of cooling may also be regulated by using the caps 22 and 24 since these caps will con-

fine the air within the apparatus and will thereby effect a much slower rate of cooling.

50 Although certain specific embodiments of the invention have been illustrated and described, it will be understood that the invention is capable of further modification and that further changes in the construction and in the arrangement of the various cooperating parts may be made without departing from the spirit or scope of the invention as expressed in the following claims.

55 What I claim is:—

1. In combination, a receptacle, an investment holder having substantially vertical, spaced walls and connecting portions extending through the length of said walls, said investment holder having flanges extending laterally and outwardly from one end thereof, shaped to fit the inner wall of the receptacle.

60 2. In combination, a receptacle having an imperforate cylindrical wall, an investment holder having substantially vertical, spaced walls and connecting portions extending throughout the length of said walls, and curved in section to fit the inner surface of the receptacle wall.

65 3. In combination, a receptacle having an imperforate cylindrical wall, an investment holder having substantially vertical, spaced walls and connecting portions extending throughout the length of said walls, and curved in section for at least a portion of their length to fit the inner surface of the receptacle wall.

70 4. In combination, a receptacle, an investment holder having a pair of straight, flat sides spaced from each other and from the receptacle wall and having ends curved to fit the receptacle wall and connecting said sides throughout their length.

75 5. In combination, a receptacle having an apertured bottom, an investment holder having a pair of straight flat sides spaced from each other and from the receptacle wall and having ends connecting said sides throughout their length, the distance between the spaced sides of the holder being less than the maximum dimension of the opening in the receptacle bottom.

80 6. In combination, a receptacle, an investment holder having a pair of straight, flat sides spaced from each other and from the receptacle wall and having ends connecting said sides throughout their length, the sides being narrower at their lower ends than at the upper ends.

85 7. In combination, a receptacle, an investment holder having a pair of straight, flat sides spaced from each other and from the receptacle wall and having ends connecting said sides throughout their length, and flanges extending outwardly from the upper ends of the holder sides.

90 8. An investment holder having a pair of

parallel plates, curved connecting walls between said plates and segmental flanges extending laterally from said connecting walls.

9. In combination, a receptacle, an investment holder therein having a pair of parallel plates, curved connecting walls between said plates and segmental flanges extend-

ing laterally from said connecting walls, said flanges conforming in curvature to the inner surface of the receptacle.

10

In witness whereof, I have hereunto set my hand this 22d day of March, 1922.

MARTIN F. BURNS.
